UNITED STATES PATENT OFFICE

113,210

DESIGN FOR A SMOCKED TEXTILE FABRIC OR SIMILAR ARTICLE

Helena S. Sadtler, Chestnut Hill, Pa.

Application November 6, 1936, Serial No. 65,725

Term of patent 7 years

To all whom it may concern:

Be it known that I, Helena S. Sadtler, a citizen of the United States and resident of Chestnut Hill, in the county of Montgomery and State of Pennsylvania, have invented a new, original, and ornamental Design for a Smocked Textile Fabric or Similar Article, of which the following is a specification, reference being had to the accompanying drawing, forming part thereof.

The figure of the drawing is a face view of a smocked textile fabric showing my design.

The characteristic feature of the design resides in the combination on the fabric disclosed of the embroidered secondary needlework arranged on a smocked background as shown.

I claim:

The ornamental design for a smocked textile fabric or similar article, as shown and described.

HELENA S. SADTLER.
